JOHN C. FLYNN, OF MOUNT VERNON, NEW YORK, ASSIGNOR TO GEORGE W. HELME COMPANY, OF NEW YORK, N. Y., A CORPORATION OF NEW JERSEY

DIPPER FOR SNUFF OR THE LIKE

Application filed December 29, 1928. Serial No. 329,210.

This invention is an improvement in dippers for snuff or the like, and more particularly in a dipper connected with the cover in such manner that the cover forms a handle 5 for the dipper.

It is desirable in the retailing of snuff that some form of dipper be furnished in connection with the retail container, either to be given with the container, or to be sold separately.

One of the primary objects of the present invention is the provision of a construction of dipper or spoon, wherein the dipper forms a permanent part of an element of the container, and wherein when the elements of the container are in normal position, the spoon or dipper will be protected by the container.

Another object is the provision of a simple and relatively inexpensive form of dipper, 20 capable of attachment to existing containers of usual construction.

With these and other objects in view the invention consists in the construction and novel combination of parts fully described 25 hereinafter, illustrated in the accompanying drawings, and pointed out in the claims appended hereto, it being understood that various changes in the form, proportion, size and minor details of construction within the 30 scope of the claims, may be resorted to without departing from the spirit of the invention.

In the drawings forming a part hereof:—

Fig. 1 is a vertical section of a container 35 for snuff provided with the improved dipper.

Fig. 2 is a perspective view of the dipper supporting element looking from the underside.

Fig. 3 is a side view of a container with 40 the cover in section showing an alternate construction.

Fig. 4 is a perspective view of the spoon carrying element looking from the upper side.

The embodiment of the invention of Figs. 45 1 and 2 is shown in connection with a container of usual construction, including a body 1 and a flanged cover, the body of which is indicated at 2, and the flange at 3. The flange fits about the open top of the body 1, and 50 the said body is provided with a circumferen-

tially extending bead 4 which forms a limiting means for the downward movement of the cover.

The dipper or spoon is formed from suitable sheet material, being cut or stamped from the sheet, to provide a suitable spoon portion 5, and a flange 6. The spoon portion is transversely curved into trough form as shown, and the large end thereof is rounded. The flange 6 is bent at right angles to the spoon, and it is connected with the body 2 of the cover by soldering, welding or brazing, indicated at 7. In the present instance, the flange is notched to provide a forked construction as shown.

The flange is connected to the inner face of the body of the cover, in a manner such that the spoon portion 5 is spaced apart from the flange, a distance corresponding substantially to the thickness of the body wall. The arrangement is such that the spoon portion 5 will extend into the container when the cover is in place, and it will be apparent that when the cover is removed it forms a handle for the spoon.

In the embodiment of the invention shown in Figs. 3 and 4, the spoon indicated at 8 is soldered or otherwise secured directly to the outer face of the flange 9 of the cover, the cover including the flange and the body 10. The spoon is curved transversely in the same manner as the spoon 5, and on an arc having its center in the axis of the container, so that when the cover is in place, the curvature of the spoon will correspond to the 85 curvature of the outer surface of the body wall, and will lie closely and against, as shown in Fig. 3.

In both embodiments of the invention the cover serves as a handle for the spoon, and in both instances it extends along the wall of the cover lying close thereto, so as to occupy a minimum of room, whether in the container or outside of the same.

What is claimed as new is:—

1. The combination with a can for snuff or the like, of a flanged cover, a spoon or dipper permanently connected with the cover in position to lie close against and substantially parallel with the side wall of the can 100

when the cover is in place, the spoon being curved transversely throughout substantially its entire length to provide a concave surface for the snuff, and the curvature conforming 5 to the curvature of the side wall of the can whereby to enable a close position of the spoon against the wall.

2. In combination with a cylindrical can for snuff or the like, a flanged cover, and a 10 spoon including a dipper portion and a base portion bent at a right angle thereto, the dipper portion being transversely curved to conform to the curvature of the can body wall, and the base portion being soldered to 15 the inner face of the cover top near its periphery, whereby the dipper portion is located close against the inner face of the can body when the cover is placed thereon.

3. In combination with a cylindrical can 20 body, a flanged cover therefor and a spoon permanently connected to the outer face of the cover flange and extending axially of the can body in contact with its outer face, the spoon being transversely curved to fit the 25 contour of the can body.

Signed at New York, in the county of New York and State of New York, this 26th day of December, A. D. 1928.

JOHN C. FLYNN.
